ANGUS A. MCKENZIE, OF CAMBRIDGE, MASSACHUSETTS.

FOLDING SUPPORTING-FRAME FOR PORTABLE HAND-VISES.

1,151,959.

Specification of Letters Patent. Patented Aug. 31, 1915.

Application filed April 2, 1915. Serial No. 18,809.

To all whom it may concern:

Be it known that I, ANGUS A. MCKENZIE, residing at Cambridge, in the county of Middlesex and State of Massachusetts, have invented a new and useful Improvement in a Folding Supporting-Frame for Portable Hand-Vises, of which the following is a specification.

My invention relates to improvements in portable hand vises, and the object of the same is to provide a folding supporting frame which is simple in construction and which permits the folding of parts thereof for rendering the device compact when the same is not in use or while the same is being carried about in the workman's kit or tool-chest.

Another object is to provide a folding supporting frame for portable hand vises which is designed to afford excellent gripping means, and which can be readily set up into working position by the clamping of the folding standards into the supporting positions.

Another object is to provide a skeleton frame for portable vises, provided with folding standards, which may be readily set into working position for rigidly supporting the frame of the vise when the same is to be used, and which otherwise may be folded back with the frame in a compact manner, occupying the least space possible and offering a most convenient and serviceable portable vise which possesses all the good working qualities of the best known vises.

Still another object is to provide a folding supporting frame for portable vises which normally may be folded into a compact space and otherwise may be temporarily or permanently set up into working order by the unfolding of pivoted standards and securely clamping the same into the supporting position;—the vise consisting of a rigid skeleton frame member having one fixed jaw and one movable co-acting jaw, which is actuated by the turning of a crank, provided for the purpose, and the said pivoted standards which are pivotally secured to said skeleton frame member for supporting the same in the working position of the vise.

To these as well as other ends, my invention consists in the novel features of construction, combination and arrangement of parts set forth in the following specification, and particularly pointed out in the subjoined claims.

Referring to the accompanying two sheets of drawings,—Figure 1, is a plan view of the vise with the standards set and clamped in the working position. Fig. 2, is an elevation of the vise, showing the same set in working position, with the jaws holding and gripping a piece of wood, or other material, between them. Fig. 3, is an elevation corresponding to Fig. 2, but shows the folding standards set and clamped in the non-working position. Fig. 4, is a section taken on line 4—4 in Fig. 1, looking in the direction of the arrows. Fig. 5, is a perspective view of the vise set in working position on a carpenter's horse, ready for operation. Fig. 6, is an end view of the vise, showing the stationary jaw which is preferably made integral with the frame. Fig. 7, is a view taken on line 7—7 in Fig. 1, looking in the direction of the arrows, showing the movable jaw of the vise. Fig. 8, is a plan view corresponding to Fig. 1, which shows the standards folded in the non-working position. Fig. 9, is a section taken on line 9—9 in Fig. 8, looking in the direction of the arrows, showing the clamping-screw which is used to secure the standards in either the working or the non-working positions.

Like numerals refer to like parts throughout the several views of the drawings.

The numeral 1 is a frame member provided with the sides 2 and 3, the stationary-jaw 4, the stop-lugs 5, and the pivoting-bosses 6. The jaw 4 is provided with the bearing-boss 7, and the opposite end of the frame 1 is provided with the bearing-boss 8 which form the bearings for the feed or operating-screw 9. 10 is the movable jaw member which is provided with the upper-guide-flanges 11, the lower-guide-flanges 12, and the tapped-hole 13, in which the feed-screw 9 operates,—the latter being held in operating position by the collar 14 which is pinned thereto for holding the same in the operating position.

Fixed to turn with the end 15 of the feed-screw 9 is the operating-crank 16 which may be secured to the feed-screw in any suitable manner, as for example, by the pin 17. The folding standards 18 are pivotally secured to the ends of the frame 1 by the pivot-screws 19 and the clamping-studs 20, which studs 20 are provided with the winged-nuts 21 by means of which the standards 18 may be secured into the required positions. The upper ends 22 of the folding-standards 18

are provided with the stop-lugs 23 which butt against the sides of the stops 5 of the frame 1, when set in the working position, as shown in Figs. 1, 2 and 5. The lower ends of the standards 18 are provided with the supporting-flanges 24 which are preferably provided with the holes 24^a, for permanently securing the vise to the work-bench, et cetera, when so desired. The flanges 24 may be provided with downwardly projecting loops 25 for forming a shoulder to allow a purchase against the work-bench, as shown in Fig. 5.

The inner ends of the sides 2 and 3, toward the crank-end of the frame 1, are provided with the recesses 26 to permit the insertion of the movable jaw member within the frame member, so that the lower-guide-flanges 12 may engage with the under sides of the frame guides 2 and 3 as shown in Figs. 1 and 2.

Having thus described the parts of my invention in detail, the mode of operation is as follows. The various parts of the device may be assembled in the following manner: The movable-jaw member 10 may be engaged with the frame member by inserting the guides 12 within the recesses 26, provided at the crank-end of the frame, which permits the jaw member to be lowered into position where the same may be set on to the guide-runs 2 and 3 of the frame member. The operating-screw 9 may then be inserted from the crank-end side through the bearing 8, when the collar 14 may be set over the same, and thereafter the operating-screw 9 may be screwed into the tapped-hole 13, provided in the movable-jaw member 10 for the purpose. The leading end of the operating-screw 9 may then be set in the bearing 7, provided on the stationary-jaw-end of the frame member. Upon thus setting the screw into its bearings, the collar 14 is then pinned into position with the operating-screw 45 which prevents the same from backing out through the bearing on the crank-end of the frame member. The operating-crank 16 may be pinned, or otherwise attached, to the operating-screw in any suitable manner. The standards may then be secured with the pivot-studs 19 and 20 to both ends of the frame member 1, as shown in the drawings. The studs 20 are provided with the winged-nuts 21, by means of which the standards 18 are rigidly secured to the frame member in the working or non-working positions, corresponding to Figs. 2 and 3, respectively of the drawings. It may be observed that the standards 18, when set into the unfolded position which is the working position, are allowed to butt up against the sides of the stop-lugs 5, as shown in Fig. 2, and when in the folded position which is the non-working position, are allowed to butt up against the bottoms of the stop-lugs 5, as shown in Fig.

3,—thus the stop-lugs serve to limit the supporting standards in either the folded or the unfolded position. The winged-nuts 21 afford a very convenient means of securing the supporting-standards in either of its positions. By manipulating the crank 16 in either direction, the movable-jaw may be advanced toward the stationary-jaw for gripping material or objects between them, or may be moved in the opposite direction away from the stationary-jaw;—thus providing positive gripping means between the two jaws for holding articles or material between them, and affording a wide range of action for operating on various widths of articles or materials.

It may thus be observed that the vise, as I have shown it, provides a very simple and effective device which may be used by workmen of various trades, permitting them to equip their kits or tool-chests with a compact form of portable vise, which consumes the least amount of space without burdening the same with any excessive weight, and at the same time provides them with an absolutely positive and efficient form of vise which may be readily set into working position, and which may be positively relied upon for best service.

It may also be observed that the operating-screw may be threaded with a fine or coarse thread, according to the grade of work the vise is to be used in,—thus affording a vise which may be constructed to suit the conditions of the special lines of work required in the various trades.

While the preferred embodiments of the invention have been described in detail, it will be understood that I do not wish to be limited to the particular construction set forth, since various changes in the form, material, proportion and arrangement of parts, and in the details of construction may be resorted to without departing from the spirit and scope of the invention, or destroying any of the advantages contained in the same, heretofore described and defined in the subjoined claims.

What I claim is—

1. A folding supporting frame for vises, consisting of a rectangular frame member provided with an upwardly projecting end for forming the stationary jaw of the vise, end-bearings for supporting the operating screw of the vise, and stop-lugs projecting outwardly from the sides of said frame member and positioned near the ends of the same; a pair of foldable supporting standards swingingly secured to said frame member near the ends of the same, provided with limiting-lugs at their secured ends for engaging with said stop-lugs when set in the "open" position, and adapted to fold and close with said frame member; and locking members, securing said foldable supporting

standards with said frame member and adapted to lock the former into the "open" or "closed" position with the latter.

2. A folding supporting frame for vises, 5 consisting of a rectangular skeleton frame member having the two longitudinal sides of the same adapted to form the runs for the movable jaw of the vise, one of the ends of the same projecting upwardly for forming 10 the stationary jaw of the vise, both ends of the same supplied with longitudinal bearings for supporting the operating screw of the vise and each side of the same provided with outwardly projecting stop-lugs near 15 the ends of the same; a pair of transverse supporting standards swingingly secured to the sides of said frame member at the ends

of the same, adapted to fold and close with said frame member, and provided with limiting-lugs at their secured ends for engaging with said stop-lugs when set in the "open" position with the frame member, and supporting flanges on the free ends of the same provided with apertures for anchoring purposes; and pivoting members provided 25 with clamping means for swingingly engaging said standards with said frame member and adapted to lock the former in the "open" or "closed" position with the latter.

ANGUS A. MCKENZIE.
